GAS BURNER

Application filed January 29, 1932. Serial No. 589,736.

This invention relates to a gas burner expressly designed for consuming natural gas and primarily, but not necessarily, intended to be employed for special work in dental laboratories and the like.

In perfecting a structure to accomplish the desired result, we have evolved and produced a novel assembly of carefully selected parts structurally co-ordinated and appropriately proportioned and matched to provide a resultant product which is efficient in performance, positive and dependable in action, smooth and quiet in operation, and otherwise susceptible of fulfilling the requirements beyond expectation.

A structure characterized by the aforesaid details and properties is by way of comparison with known prior art burners, an appreciable contribution to the art and trade embodying such advantages and indispensable features as appropriately controlled combustion, practical heat radiation, safety of adjustment and maintenance, and simplicity and economy in manufacture and sale.

Other objects and mechanical achievements embodied in the complete structural organization will become more readily apparent to persons skilled in the art as the detailed description is read in conjunction with the accompanying drawing:

In the drawing:

Figure 1 is a top plan view of the preferred embodiment of our invention.

Figure 2 is a central vertical sectional view taken approximately on the plane of the line 2-2 of Figure 1.

Although the structure is individualized by a plurality of distinguishable parts and details, it is essentially composed of a unique base and superstructure supported on said base. The base is generally designated by the numeral 3 and comprises an elevated plate 4 imperforate except for a single opening formed adjacent the central portion thereof. This plate constitutes an integral part of a tripod including radial strap like legs 5 appropriately curved and terminating in supporting feet 6.

One of the legs, which may be conven-

iently referred to as the front leg includes an extension 7 provided with a retaining hole. Associated with this leg and preferably formed integrally therewith is an outstanding supporting bracket 8 formed with an upstanding free end portion 9 terminating in a terminal 10 formed with a screw-threaded hole to accommodate the screw-threaded nozzle 11 of the supply hose attaching fixture 12.

It will be observed that this fixture includes a hose attaching nipple 13 appropriately constructed to accommodate and retain the supply pipe or hose (not shown). The entire fixture 12 is adjustably supported in the part 10 of the bracket. The passage through said fixture is constricted and gradually reduced at the point 14 and is further constricted at 15 to form a gas discharge orifice of desired proportion.

The removable unit 16 comprises a suitably shaped and proportioned perpendicular casing 17 having its upper end reduced as at 18 and constructed to receive and support a removable grid 19. The grid 19 is formed with a multiplicity of flame discharge slots 20. Attached to the lower portion of one of the side walls of the casing and extending horizontally is a primary mixing chamber in the nature of a tube 21 and this has an enlarged outwardly flared air intake 22 into which the nozzle 11 projects concentrically in the relative position disclosed in Figure 2.

The numeral 23 merely designates a depending lug carried by the tube 21 and seated in the aperture in the part 7 of the plate to aid in stabilizing and maintaining the parts in assembled relationship.

An additional feature of security is provided in the form of a horizontal cross rod 24 mounted in the lower end portion of the casing with its ends suitably connected to opposed side walls of the casing and provided with a depending screw-threaded stud 25 suitably connected with an intermediate part of the cross rod and which extends down through the opening in the plate 4, the screw-threaded end being exposed to accommodate an easily accessible thumb

nut 26 which provides the primary clamping and retention means.

An essential part of the invention is denoted by the numeral 27 this being in form 5 of a disc adjustably mounted on the threaded nozzle and movable toward and from the air intake 22 to function as a primary air adjustment and further as a shield to minimize the possibility of clogging from molten 10 wax or metals such as might otherwise be the case when used in laboratories and the like.

It is evident that the detachable unit 16 clamped and appropriately supported on the 15 base 3 provides a novel assembly susceptible of separation for cleaning purposes. This unit 16 is important in that it constitutes the primary air mixing chamber (tube 21) and the secondary mixing chamber (casing 20 17). The method of providing a dependable quick separable connection between the part 3 and 16 is a distinctly practical and modern arrangement.

This is true because of the scientific selection 25 and unification of parts capable of promoting stability and rigidity. Considerable importance is attached to the tripod like base with its elevated plate 4, feet equipped legs to permit air circulation beneath the base, and the L-shaped bracket 30 8 serving to accommodate the adjacent accessories. The fixture 12 is bodily movable, and the disc 27 is independently adjustable to afford the desired air regulating 35 features.

In practice, this part 27 is of a diameter corresponding approximately to the flared air intake 22. It is evident therefore that all of the parts co-operate in producing a 40 successful structure which, it is believed, will supersede similar prior art devices embodying analogous fundamental features.

It is thought from the foregoing description 45 that the advantages and novel features of the invention will be readily apparent.

It is to be understood that changes may be made in the construction and in the combination and arrangement of the several parts provided that such changes fall within 50 the scope of the appended claims.

We claim:

1. In a structure of the class described, a base embodying a plate having marginal supporting legs, a vertically elongated open-

55

ended casing removably seated on said base and provided with an outstanding injector tube within the vicinity of the base, a removable grid mounted in the upper portion of said casing, a cross-rod mounted in the lower portion thereof and provided with a depending screw-threaded retaining stud extending down through an opening in the adjacent portion of said plate, a clamping nut carried by the screw-threaded part of the stud for detachably securing the casing to the base.

2. In a structure of the class described, a base embodying a plate having marginal supporting legs, a vertically elongated open-ended casing removably seated on said base and provided with an outstanding injector tube within the vicinity of the base, a removable grid mounted in the upper portion of the casing, a cross-rod mounted in the lower portion thereof and provided with a depending screw-threaded retaining stud extending down through an opening in the adjacent portion of said plate, a clamping nut carried by the screw-threaded part of the stud for detachably securing the casing to the base, a bracket mounted on said base and projecting outwardly beyond the adjacent intake end of said tube, a fixture constructed to accommodate a gas supply hose and including a screw-threaded nozzle adjustably mounted in said bracket and projecting into the adjacent end of the tube, and a screw-threaded washer mounted on said nozzle and adjustable toward and from said tube.

3. A gas burner of the class described comprising a base, a plain upright casing having its lower end detachably connected to the base with its upper end reduced, a grid removably arranged in the said reduced upper end of the casing, a horizontally arranged injector tube having one end connected with a side portion of the casing adjacent the lower end thereof with the tube in communication with the lower part of the casing, a bracket supported from the base and having an upstanding portion arranged in front of the free end of the tube, a nozzle passing through said part of the bracket and extending into the free end of the tube.
